UNITED STATES PATENT OFFICE.

ALPHEUS FAY, OF COLUMBIA, TENNESSEE, ASSIGNOR OF ONE-FOURTH TO
ZILLMON SMITH, OF MAURY COUNTY, TENNESSEE.

CAR-COUPING.

SPECIFICATION forming part of Letters Patent No. 293,727, dated February 19, 1884.

Application filed June 5, 1883. (No model.)

To all whom it may concern:

Be it known that I, ALPHEUS FAY, of Columbia, in the county of Maury and State of Tennessee, have invented certain new and useful Improvements in Car-Couplings; and I do hereby declare that the following is a full, clear, and exact description thereof, reference being had to the accompanying drawings, and to the letters of reference marked thereon, which form part of this specification, in which—

Figure 1 is a bottom view of the ends of two freight-cars having my improved self-couplings applied, the cars being uncoupled. Fig. 2 is a vertical section taken longitudinally and centrally through Fig. 1, showing the cars coupled, and also showing a coupling-link applied. Fig. 3 is a view of one end of a car having my improved self-coupling applied to it. Fig. 4 is a perspective view of one part of the improved draw-bars and its hook made in one piece.

This invention relates to what is known as self-couplings for railroad-cars; and it consists in a novel combination of spring-actuated hooked draw-bars with levers for uncoupling the hooks, all of which will be fully understood from the following description when taken in connection with the annexed drawings.

Before describing my invention, I will state that I am aware that self-coupling spring-actuated hooks for cars are old and well known, and for this reason I do not claim, broadly, such hooks.

A A designate the ends of two freight-cars, to which my improved self-coupling is applied; and B B designate two draw-bars, which are allowed endwise and lateral movement, controlled by springs C C, applied between transverse sill-beams D D. The outer ends of the draw-rods a a, which pass through said springs and beams, are connected to the inner ends of the draw-bars by means of pivots e e, and these draw-bars are acted on by springs E E, which hold them against the ends of openings p, made through the transverse and supporting beams J, which are rigidly secured to the car-bed. The springs E E keep the draw-bars always in a position for effecting a coupling when two cars come together.

G G are coupling-hooks having beveled ends, as shown in the drawings. These hooks are formed on the ends of the draw-bars B B, and

are located on the vertical edge of the side walls, w. Each draw-bar has a hollow head, B', presenting one vertical side, a horizontal roof having a beveled edge, and a floor also having a beveled edge. It will thus be seen that each draw-bar has one side open, the object of which is to allow the hooks G to be uncoupled by swinging either one of the draw-bars laterally.

L designates a hand-lever, which has its fulcrum on the end of a car, and which is connected by a link to the head of the draw-bar and acted on by a spring, S. This spring operates to prevent a casual detachment of one coupling-hook from another.

At b b holes are vertically made through the draw-heads for the purpose of receiving pins n, for coupling a car provided with my coupling, with a car not so provided by means of the well-known link N, as shown in Fig. 2.

It will be observed that the open heads of the draw-bars are adapted to serve as buffers, as well as draw-heads; also, that an uncoupling of the hooks G can be effected by a movement of one lever, L.

Having thus fully described my invention, what I claim as new, and desire to secure by Letters Patent, is—

1. The combination of a pivoted draw-bar, a three-sided flaring-mouth draw-head, and a coupling-hook formed on the end of the vertical side of this head, all constructed and adapted to operate substantially in the manner and for the purposes described.

2. Vibrating spring-actuating draw-bars having three-sided draw-heads and coupling-hooks formed on them, in combination with the side springs, E, beams J, in which the draw-bars are guided, levers L, connected to the draw-bars, and springs acting on said levers, all constructed and adapted to operate substantially in the manner and for the purposes described.

In testimony that I claim the foregoing as my own I affix my signature in presence of two witnesses.

ALPHEUS X FAY.
mark.
